UNITED STATES PATENT OFFICE.

GEORGE C. WENZELL, OF GERMANTOWN, PENNSYLVANIA.

CORSET-CLASP.

SPECIFICATION forming part of Letters Patent No. 761,931, dated June 7, 1904.

(Application filed December 10, 1901. Serial No. 85,340. No model.)

To all whom it may concern:

Be it known that I, GEORGE C. WENZELL, a citizen of the United States, residing at Germantown, county of Philadelphia, State of Pennsylvania, have invented a new and useful Corset-Clasp, of which the following is a true and exact description and specification.

The corset-clasps heretofore and at present in use consist of two strips of thin steel or other elastic material, one strip bearing lugs or ears of metal with holes or eyes terminating in narrow slots horizontally thereto and the other strip carrying pins or studs which protrude therefrom. When the strips are brought together, each pin enters the eye of its opposite lug and is then led by muscular pressure of the body horizontally into the slot, which permits the body of the pin to pass, but prevents the passage of the head thereof, thereby retaining the pin at the termination of the slot, from which it may be disengaged by pressing the pin backward in the direction in which it entered until the head may be withdrawn through the eye. There are many disadvantages incident to this construction, the more important being that involuntary disengagement is very apt to occur, either by the pressure of the body when stooping or bending forcing the pin backward into the eye, through which it slips, or by the breaking of the strip of steel owing to the strain imposed thereon by muscular pressure and the absence of efficient elasticity due to the horizontal formation of the slot.

By my invention all difficulties are most effectually overcome, the objects of said invention being, first, to attain greater vertical flexibility of the corset when clasped and, second, to securely lock the pins or studs in the slots. I attain these objects by the construction shown in the accompanying drawings, forming part of this specification, wherein—

Figure 1 is a plan view of my improved interlocking corset-clasp, representing the strips disengaged and showing the pins opposite the termination of the slots. Fig. 2 is a plan view representing the said strips in juxtaposition, the upper pins engaging and pushed to the extremities of their respective slots and show-

ing in dotted lines the position of the lower or locking pin with respect to the eye of the locking-slot. Fig. 3 is a plan view representing the strip carrying the pins, the same being depressed in the act of permitting the locking-pin to engage the eye of the locking device. Fig. 4 is an edge view of Fig. 3; and Fig. 5 is a plan view of the clasp at rest or in operative position, showing all the pins in the series at the extremities of their respective slots, which result follows upon the release of the elastic strip subsequently to the engagement of the locking-pin with the eye of the locking device.

Similar letters of reference designate corresponding parts throughout the several views.

My invention and construction consists of two strips of thin steel A and B or other suitable elastic material, one of which, A, carries pins or studs C, provided with heads D, Fig. 4. In this respect and to this extent my clasp is not unlike those already in use, and I make no claim thereto except in combination with novel features which lie in the peculiar and particular formation of the eye and slot in the lugs or strips of elastic material and the arrangement of one eye and slot in the series and its corresponding pin with respect to each other and the formation of said eye and slot with respect to the other eyes and slots in the series, to wit: The other strip, B, carries one or more lugs or ears E, each of which is provided with an eye F of any desired shape so as to admit the head of the corresponding pin C. This eye terminates in a perpendicular slot G, running longitudinally of the strip or busk or vertical or perpendicular with respect to the body of the wearer when the corset is in use. Said slots all run in the same direction, are closed at their free extremities, and are of a width less than the diameter of the head of the pin and greater than the cylindrical diameter of its body and are of equal length. Preferably they connect with the eyes at their sides, and the outer edge of said slots connect tangentially with the periphery of the eyes, as indicated at g—that is, the outer vertical or perpendicular line of the slot at its point of meeting with the curved line 100

of the eye has the same direction as the said curved line. This particular formation of eye and slot may be made in the strip of steel or busk itself and not in lugs, as shown.

5 Another element of my invention is a locking device, which is preferably located at the bottom of the series and usually consists of a lug *J*, provided with an eye *K*, which terminates in a longitudinal (with respect to the busk) slot *L*, depending from it and in a reverse direction to the rest of the slots in the series. The eye *K* is so placed with respect to its corresponding pin or stud *M* that when the upper pins *C* are inserted in their respective eyes *F* and pressed upward to the extremities of the slots *G* the pin *M* will be adjacent outside the terminal vicinity of the slot *L*, as shown in Fig. 2, but cannot enter it until made to do so by springing or bending the strip *A*, carrying the pin *M* upward until the said pin engages the eye *K*, conveniently placed for such purpose, as shown in Figs. 3 and 4. Upon releasing the strip the pin *M* will glide into the downwardly-depending slot *L* and be held therein by the natural elasticity of the ribbon of steel, yet at the same time being permitted vertical or longitudinal play therein to relieve strain thereon due to the movements of the wearer of the corset, as shown in Fig. 5. Thus when in operation all the pins in the clasp are seated at the extremities of their respective slots. The eye and slot of the locking device may be of any desired formation, providing the eye is either above or below the slot, according as to whether the device or locking arrangement is at the top or bottom of the series, or said eye and slot may be formed in the metallic strip itself; but I prefer the construction shown. The locking arrangement may be reversed by placing it at the top of the series, in which case its slot would be upward in direction or over the eye and the slots of the other lugs in the series would be downward with respect to their eyes.

15 The operation of my construction is as follows: The pins or studs *C* are inserted through the eyes *F* of the lugs *E* and are slid into the slots *G*. The eye *K* and pin *M* of the locking device are not at this time (as before set forth) longitudinally opposite each other. Therefore in order to permit the pin to engage the eye the direct distance between said pin and the one above it must be shortened, 20 which is done by depressing or elevating into

an arc the elastic ribbon of metal to the engaging-point, when by releasing the arc thus formed after the pin has engaged the eye the chord lengthens until it and the arc coincide, the pin being conveyed to the termination of its slot *L* and the clasp securely locked. The pins *C* travel readily from the eyes *F* into the vertical slots *G* along the tangent *g* thereof—that is, the vertical line of the slot at its point of meeting with the curved line of the eye having the same direction as said curved line permits easy and expeditious locking of the clasp. The verticality of the slots allows greatly increased freedom of vertical motion and also of muscular action in any direction by the wearer of the corset and relieves all undue strain on the strips, thus avoiding premature breaking thereof. The pins engaging the slots at right angles to the line of bodily pressure form a series of sliding joints, with the result of decreased resistance to forward, backward, and sidewise bending of the body, and greatly lengthens the life of the elastic ribbons connecting the eyes and the pins, while at the same time the retention of the locking-pin in its slot by means of the elasticity of the ribbon of metal prevents most effectually premature disengagement of the clasp, and this is so no matter to what extent the corset is laced or unlaced in the rear.

25 Having now described my invention, what I claim as new, and desire to secure by Letters Patent, is—

30 A corset-clasp consisting of two strips of elastic metal; a series of headed pins arranged on one of said strips; a series of eyes arranged on the other strip; perpendicular slots of equal length running in the same direction and longitudinally of the busk, closed at their upper extremities and connecting at their lower extremities with said eyes at the sides thereof, the outer edge of said slots connecting tangentially therewith; and an eye in the series terminating in a slot of less diameter and depending therefrom in a reverse direction to all the other slots in the series and so arranged that when the clasp is in operation all the pins in the series will rest at the extremities of their respective slots, substantially as shown and described.

35 GEORGE C. WENZELL.
